[57] CLAIM

The ornamental design for a locking device for vehicles, as shown and described.

DESCRIPTION

FIG. 1 is a perspective view of a locking device for vehicles showing my new design, it being understood that the broken lines are for illustrative purposes only; FIG. 2 is an enlarged front elevational view thereof; FIG. 3 is a rear elevational view of FIG. 2; FIG. 4 is a side elevational view of FIG. 2; FIG. 5 is an elevational view of the opposite side of FIG. 2;

FIG. 6 is a top plan view of FIG. 2; and

FIG. 7 is a bottom plan view of FIG. 2.

The locking device has been broken away in the middle in FIGS. 1, 2, 3, 4 and 5 to indicate indeterminate length.
